UNITED STATES PATENT OFFICE.

FRED LICHTENBERG AND MICHAEL M. McCARTHY, OF YONKERS, NEW YORK.

FLOOR SLAB.

Application filed November 16, 1921. Serial No. 515,452.

To all whom it may concern:

Be it known that we, FRED LICHTENBERG and MICHAEL M. McCARTHY, citizens of the United States, and residents of Yonkers, 5 Westchester County, and State of New York, have invented certain new and useful Improvements in Floor Slabs, of which the following is a specification.

Our present invention relates particularly 10 to floor structures.

The objects of the invention are to provide a slab construction for flooring or other purposes which will be automatically interlocked and keyed together as the structure 15 is built up and which will hold the keying or bonding material without the necessity of any special forms.

These and other advantageous results are attained in our invention by means of cer- 20 tain novel features of construction, combi- nation and relation of parts, a typical ex- ample of which is given in the accompanying drawing forming part of this specification.

In the drawing referred to, Figure 1 is a 25 cross sectional view of one of our building slabs and the adjoining portion of another, illustrating the manner in which the interlock and bonding between the slabs is effected.

Figure 2 is a broken plan view of a single 30 slab.

Figure 3 is a broken plan view of a floor made up of these slabs.

The slabs, which are designated 5, are con- 35 structed of concrete or other suitable cementitious material, of a size and shape to suit any usual or special requirements. They also are preferably suitably reinforced. In the illustration this reinforcement is effected 40 by providing a double layer of reinforcing rods or wires, located one layer adjacent each face of the slab. The rods of the two series are designated 6 and 7 respectively, and are shown as spaced equal distances 45 apart but arranged with the rods in one layer diagonally offset from the rods in the opposite layer. The rods are held in this spaced relation by suitable connecting tie wires 8 and the rods of the two layers are 50 tied together by diagonally extending tie ele- ments 9 which may be formed by lacing wires diagonally back and forth between the rods of the two layers.

A special feature of the reinforcing rods 55 6 in the uppermost layer in Figures 1 and 2 is that the outer rods are supported by the

positioning wires 8 offset in spaced relation at the edges of the slab so as to operate as ties between adjoining slabs and form reinforcements for the bonding material used 60 between the adjoining slabs.

The bonding of the adjoining slabs is ac- 65 complished in our invention by providing the slabs along their longitudinal edges and adjacent one face of the slabs with recesses 10 which form, when the lower corner edges 70 of the slabs are brought together into abut- ting relation, closed troughs for the recep- tion of keys of bonding material at 11, Figure 1. These recesses are preferably under- 75 cut as shown in Figure 1, so as to interlock the bonding material therein and prevent the bonding keys from working loose upon contraction.

It will be noted that the outstanding rein- 75 forcements above described are located at the upper corner edges of the slab and so are disposed within the troughs formed when adjacent slabs are brought into abutting engagement. Also in the illustration the 80 exposed reinforcements, including the tie wires 8, extend far enough to project prac- tically entirely across these troughs, and hence that when the slabs are brought to- 85 gether, such reinforcements will stand in overlapping relation. This construction, 90 therefore, ties and bonds the slabs together in very secure fashion and reinforces the bonding key so that this key becomes of practically the same strength as the slab 95 itself.

If further reinforcement of the bonds is 95 desired, reinforcing elements such as the rods 12 may be laid loosely in the troughs either upon or beneath the overlapped reinforce- 100 ments described. These added reinforce- ments, as shown in Figure 3 may be extend- ed the full length of the floor and hence operate to tie the slabs together in their end-to-end relation, as well as form full 105 length reinforcements for the floor.

By way of example, we have shown in Figure 3 how in the case of building a floor, the slabs may be supported directly 110 on I-beams 13 with their longitudinal edges in abutting relation to provide the closed troughs for the bonding material and how the bonding material forming these keys may be a part of the final flooring itself.

This means that when the slabs are prop- 110 erly laid the flooring material may be flowed directly thereover, as indicated

particularly at 14 in Figure 3, said material working into the closed troughs about the reinforcements and acting as it hardens both to bond the slabs together and to serve as 5 the floor surface.

What we claim is—

1. Flooring slabs of cementitious material recessed along their upper edges to provide when the slabs are assembled with their 10 lower edges in abutting engagement, troughs open at the top to receive plastic bonding material, layers of reinforcement near the upper and lower faces of the slabs, said layers being connected in spaced relation by ties, the lower reinforcement layers including reinforcement rods extending 15 along the lower projecting abutting edges of the slabs and the upper reinforcing layers having extensions projecting past the re-

cessed upper edges of the slabs, beyond the 20 lower projecting edges thereof and across the troughs provided between adjoining slabs to thereby form a substantially continuous reinforcement and bond between the slabs. 25

2. The structure of claim 1 in which the reinforcing extensions which project beyond the recessed upper edges of the slabs carry longitudinally extending reinforcing rods standing free of the slabs by which they are 30 carried and adapted for cooperative relation with the adjoining slabs.

In witness whereof, we have hereunto set our hands, this 3rd day of November, 1921.

FRED LICHTENBERG.
MICHAEL M. McCARTHY.
